ELECTRIC SWITCH

Filed Jan. 2, 1926

UNITED STATES PATENT OFFICE

JOHN B. TRECSCOTT, OF ST. LOUIS COUNTY, MISSOURI, ASSIGNOR TO JAMES R. KEARNEY CORPORATION, OF ST. LOUIS, MISSOURI, A CORPORATION OF MISSOURI

ELECTRIC SWITCH

Application filed January 2, 1926. Serial No. 78,881.

My invention relates to a new and useful improvement in switches and more particularly to high tension switches which are utilized on power transmission poles to make and break the circuit for various purposes. The principal object of my invention is to provide a blade receiving contact that will grip the switch blade mechanically and form a positive contact.

Another object is to provide a mechanically gripping receiving contact that will become released upon backward movement of the switch blade.

A still further object is to provide a control handle that throws past a dead center, one side of which when the switch is closed tends to further close the switch by the weight of the parts and the other side of which tends to hold the switch open by supporting the same weight.

With the foregoing and other objects in view, my invention consists in certain novel features of construction and arrangement of parts, hereinafter more fully described and claimed, and illustrated in the accompanying drawings, in which—

Figure 1 is a side view of my improved high tension switch and controlling handle.

Figure 2 is a top view of the contacting elements in engaged position.

Figure 3 is an enlarged side view of the contacting elements.

The numeral 1 in the drawings indicates a switch supporting frame on which is mounted a stationary insulator pin 2. Journal 3 is also mounted on frame 1 and carries a rotatable insulator pin 4. Mounted on the top of rotatable insulator pin 4 is an ordinary knife blade contacting element 5 of the type common to high tension switches. The blade receiving switch element 6 is mounted on the stationary insulator pin 2 by means of an ordinary bracket 7. This member has a comparatively heavy base 8 in which are fixed receiving blades 9 which blades 9 are normally spaced slightly closer together than the thickness of blade 5 and have their free ends flared to insure its proper introduction.

Lugs 10 and 11 which are formed with base 8 project parallel to and outside of the

receiving blades 9. Bell cranks 12 and 13 are fulcrumed by pins in the outer ends of lugs 10 and 11 and terminate in flared feet 14 and 15 adjacent to the outer ends of receiving blades 9. The opposite ends 16 and 17 of the bell cranks pass through openings 18 and 19 in the receiving blades 9 and terminate in the path of the movable blade element 5.

The rotatable insulator pin 4 carries an arm 20. Pivotedly connected to arm 20 is a length of pipe 21. The length of this pipe varies according to the particular installation but is normally from five to twenty feet long and it can be readily seen that such a weight could easily actuate the switch where provision is not made to prevent it.

Bracket 22 is located on the pole at the desired point and carries a bell crank switch actuating handle 23. The lower end of pipe 21 is connected to arm 24 of the actuating handle. When the switch is closed, as shown by the full lines in Figure 1, the weight of the pipe 21 is so directed that it tends to further close the switch. There is no limit to the closing movement of the switch throughout the controlling handle or actuating mechanism. When the switch is open as shown by the dotted lines in Figure 1, the weight of pipe 21 is directed to the other side of the axis of the handle and a stop 25 prevents excessive motion of the handle in this direction.

In the operation of my improved high tension switch, the movable blade 5 enters between the spaced receiving blades 9. Since the blades 9 are slightly closer together than the thickness of blade 5, blades 9 spread and tend to contact only with the entering edge of blade 5. This condition exists until blade 5 contacts with the arms 16 and 17 of the bell cranks 12 and 13 when the driving force of blade 5 clamps the outer ends of the spaced contacts 9 against the blade 5 through the medium of feet 14 and 15 of these bell cranks. The clamping action of the bell cranks arrests the forward motion of the blade 5 and provides a contact along the full surface of blade 5 within blades 9 as shown in Figure 2.

It will be readily seen that the force with

which blade 5 strikes the arms 16 and 17 of bell cranks 12 and 13 governs the tightness of the connection between blades 9 and blade 5. A very slight backward movement of blade 5 releases bell cranks 12 and 13 and freely permits its full withdrawal.

It will be readily understood that minor changes in the size, form and construction of the various parts of my improved switch 10 may be made and substituted for those herein shown and described, without departing from the spirit of my invention, as expressed in the appended claims.

I claim:

15 1. An electric switch comprising spaced receiving contacting elements, bell cranks mounted exteriorly of and each having an arm projecting through the said contacting elements and an arm adjacent to the free end 20 of one of said spaced elements, and a single contact blade adapted to enter between said spaced contacts and clamp their extremities by actuating said bell cranks, said clamping action forming a full length connection.

25 2. In an electric switch including a movable contact element and a stationary contact element adapted for engagement, a bell crank having an arm projecting through said stationary contact for engagement by said 30 movable contact and its other arm bearing against the outer side of said stationary contact for clamping said contacts together actuated by their engaging movement and released by the initial disengaging movement.

35 3. In an electric switch including a movable contact element and a stationary contact element adapted for engagement, a bell crank mounted adjacent to and having an arm projecting through said stationary contact for 40 engagement by said movable contact, said bell crank being adapted to clamp said contacts together to effect full length connection between said contacts upon actuation by said movable contact.

45 4. In an electric switch including a movable contact element and a stationary contact element adapted for engagement, bell cranks mounted adjacent to said stationary contact and each having an arm projecting there- 50 through for actuation by said movable contact, said bell cranks being adapted to clamp said contacts together upon engagement of said arm, and release said contacts upon slight disengaging movement.

55 5. In an electric switch, a stationary contact comprising a pair of relatively flexible members, each having a free end, a relatively rigid movable contact adapted to enter between said stationary contact members, a 60 bell crank adjacent each stationary contact member and having an arm projecting therethrough and a foot bearing against the free end, said bell crank arms being in the path of travel of said movable contact and adapted 65 for actuation thereby to clamp the free ends

of said stationary contact against said movable contact and establish a full length connection.

In testimony whereof I hereunto affix my signature this 31st day of December, 1925.

JOHN B. TRECOTT.
